[57] CLAIM

The ornamental design for a surgical access port, as shown and described.

DESCRIPTION

FIG. 1 is a top perspective view of a surgical access port of the invention in a first deployment configuration; FIG. 2 is a top elevational view of the access port of FIG. 1; FIG. 3 is a bottom elevational view of the access port of FIG. 1;

FIG. 4 is a right elevational view of the access port of FIG. 1, the left elevational view being the same; FIG. 5 is an end elevational view of the access port of FIG. 1, the other end view being the same;

FIG. 6 is a top perspective view of the surgical access port of FIG. 1, but illustrating the access port in a second deployment configuration; FIG. 7 is a top elevational view of the access port of FIG. 6; FIG. 8 is a bottom elevational view of the access port of FIG. 6;

FIG. 9 is a right elevational view of the access port of FIG. 6;

FIG. 10 is an end elevational view of the access port of FIG. 6, the other end view being the same;

FIG. 11 is a top perspective view of the surgical access port of FIG. 1, but illustrating the access port in a third deployment configuration; FIG. 12 is a top elevational view of the access port of FIG. 11;

FIG. 13 is a bottom elevational view of the access port of FIG. 11; FIG. 14 is a right elevational view of the access port of FIG. 11, the left elevational view being essentially the same; FIG. 15 is a front elevational view of the access port of FIG. 11; and,

FIG. 16 is a rear elevational view of the access port of FIG. 11.
